UNITED STATES PATENT OFFICE

90,884

DESIGN FOR A COFFEE MAKER

Donald L. Hadley, Mansfield, Ohio, assignor to Westinghouse Electric & Manufacturing Company, a corporation of Pennsylvania

Application March 3, 1933. Serial No. 47,393

Term of patent 7 years

To all whom it may concern:

Be it known that I, DONALD L. HADLEY, a citizen of the United States, residing at Mansfield, in the county of Richland and State of Ohio, have invented a new, original, and ornamental Design for Coffee Maker, of which the following is a specification, reference being had to the accompanying drawings constituting a part hereof.

Figure 1 is a front elevational view of a coffee maker showing my new design, and

Fig. 2 is a front elevational view taken from the right-hand side of Fig. 1 of my new coffee maker.

I claim:

The ornamental design for a coffee maker substantially as shown.

In testimony whereof, I have hereunto subscribed my name this 15th day of February, 1933.
